CABINET FOR CONTROL APPARATUS FOR TYPE
SETTING EQUIPMENT

Leonard S. Storch, 175 W. 72nd,
New York, N.Y. 10023

Filed Oct. 21, 1968, Ser. No. 14,093

Term of patent 3½ years

Int. Cl. D13—03

U.S. Cl. D26—13

FIG. 1

FIG. 2

FIG. 3

FIG. 4

FIG. 1 is a perspective view of the cabinet for control apparatus for type setting equipment, where the rectangles on the face of the cabinet represent raised colored strips;

FIG. 2 is a side elevation of the cabinet;

FIG. 3 is a rear elevation of the cabinet; and

FIG. 4 is a bottom view of the cabinet.

I claim:

The design for a cabinet for control apparatus for type setting equipment, substantially as shown and described.
